UNITED STATES PATENT OFFICE.

VICTOR PETERSON, OF CHICAGO, ILLINOIS.

DOOR LOCK.

Application filed November 22, 1926. Serial No. 150,014.

This invention relates to certain novel improvements in door locks and has for its principal object the provision of an improved construction of this character which 5 will be highly efficient in use and economical in manufacture.

Among the several objects of the present invention is to provide a door lock which has an electrically controlled latch bolt 10 which is operable by a selective switch for automatically throwing the latch bolt into latched position with its keeper plate whereby to lock the door from the inside of a room.

15 The latch bolt of the lock to be herein-after more fully set forth is adapted to be controlled electrically within a room including the door with which the lock is associated, whereby if one inside of the room 20 attempts to escape after committing an offense, the latch may be expeditiously thrown into latched position with its keeper plate, thus preventing the escaping person from leaving the room. It will be seen from the 25 descriptions hereinafter to follow that my improved door lock will be especially of great utility when used on the doors of a jewelry store or the like.

Other objects will appear hereinafter. 30 The invention consists in the novel combination and arrangement of parts to be hereinafter described and claimed.

The invention will be best understood by reference to the accompanying drawings, 35 showing the preferred form of construction and in which:

Fig. 1 is a vertical sectional detailed view of the invention; and

40 Fig. 2 is a diagrammatical view of a circuit embodied in the invention.

In the drawing 10 indicates a fragmentary portion of a door which has a recess 11 formed therein for confinement of the casing 12 which casing is connected to the door 45 through the medium of screw elements 13. This casing has a face plate 14 provided with an opening 15 through which projects the head 16 of the latch bolt 17 hereinafter more fully set forth.

50 A door jam is fragmentarily illustrated at 18 and this door jam has formed in its edge 19 a recess 20 which receives the head 16. Formed in this edge is a recess 21 for confinement of the keeper plate 22, said keeper 55 plate being connected to the door jam through the medium of screw elements 23,

Secured to the wall 24 of the casing 11 are pairs of spaced brackets 25 and 26. These brackets 26 support solenoid coils 27 and 28. The latch bolt 17 is formed as an 60 integral part of the solenoid 29 and moves relatively to the coil 28 when said coil is energized. A solenoid 30 works relatively to the coil 27 when said coil is energized. The inner end portions 31 of the solenoids 65 are pivotally connected, through the medium of a slot and pin connection 32 to the end portions 33 of a connecting link 34. This connecting link 34 is pivotally connected to the wall 24 through the medium of a 70 pintle 35 and pivotal movement of the connecting link is limited through the medium of stop pins 36 in the direction toward the inner end portion of the casing 11.

In Fig. 2 I have shown a preferred electric circuit and in this electric circuit 37 indicates a suitable source of electric energy. The corresponding sides of the coils 27 and 28 are connected in circuit with this electric energy through the medium of conductors 75 38. One side 39 of the source of electric energy is connected to a spaced contact 40 through the medium of conductors 41. The other side of the coils 27 and 28 are connected to contact fingers 42 through the medium of conductors 43, said contact fingers being adapted alternately to engage the contacts 40 whereby to alternately energize the coils 27 and 28. 80

The coils may be also energized from without the room and this is accomplished by providing a common key lock 44 which includes a contact finger 45 adapted to alternately contact with contact elements 46. These contact elements are connected in 85 circuit with the source of electrical energy and the coils 27 and 28 by conductors 47.

The operation is as follows: 90 When the coil 27 is energized the solenoid 30 will be caused to move relatively to the coil 27 and during this movement, movement to the solenoid 29 is imparted simultaneously with the movement of the solenoid 30 whereby to move the latch head from engagement in the keeper plate. To energize 100 the coil 27 the contact finger 42' of the contact fingers 42 is moved into contact with its respective contact 40 to connect the coil 27 in circuit with the source of electric energy.

105 When the coil 28 is energized, at which time the coil 27 is de-energized, the solenoid 29 will be moved relative to the coil 28 and 110

move the latch head 16 in latch position with respect to the keeper plate of the door jam. The energizing of the coil is accomplished by moving the contact finger 42' of the contact fingers 42, into contact with its respective contacts 40. From this it will be seen that the coil 27 is utilized for moving the solenoid 29 to disengage the latch head 16 from the keeper plate and that the coil 28 is utilized for moving the solenoid 29 to move the latch head 16 in latched position with respect to the keeper plate.

It is intended that the switch which comprises the contacts 40 and contact fingers 42 be arranged in a convenient place within the room with which the door is associated.

When it is desired to operate the latch bolt from without the room, the usual key (not shown) is inserted in the key hole of the lock 44 and when the barrel of the lock 44 is located the finger 45 will be moved into engagement with the contact element 46 in the path of its movement and energize the coil with which it is connected in circuit.

From this it will be seen that the coil may be energized by a switch located outside of the room whereby to move the latch bolt from and into latched position with respect to its keeper plate.

It will be further seen from the description herein that inasmuch as no door handles or nobs are provided that one desiring to prevent escape of a thief from a room can expeditiously do so by manually operating the switch, comprising the contact 40 and contact fingers 42 to energize the coil to move the latch bolt into latched position with respect to its keeper plate.

While I have illustrated and described the preferred form of construction for carrying my invention into effect, this is capable of variation and modification, without departing from the spirit of the in-

vention. I, therefore, do not wish to be limited to the precise details of construction set forth, but desire to avail myself of such variations and modifications as come within the scope of the appended claims.

The invention having been set forth, what I claim as new and desire to secure by Letters Patent is:

1. In combination, a keeper plate, two members movable relatively to each other, pivotally supported means for operative connection to corresponding end portions of said members, one of said members being adapted for latched engagement with the keeper plate, means for moving said members, and remote means for controlling operation of said moving means.

2. In combination, a keeper plate, two members movable relatively to each other, one of said members being adapted for latched engagement with the keeper plate, a pivotally supported member having operative connection with corresponding end portions of said members, electrically controlled elements for moving said member, and circuit making means for closing the electric circuit alternately to said moving means.

3. In combination, a casing including a face plate having an opening formed therein, magnetic elements arranged within the casing in parallel relation with respect to each other, solenoid cores operable by said elements and movable relatively to each other, a latch head formed on one of said solenoid cores and adapted to project through the opening, a link pivotally connected to the casing, a slot and pin connection between the corresponding end portions of the solenoid cores and at link member, and a circuit breaker for controlling the circuit alternately to said magnetic elements.

In testimony whereof I affix my signature.

VICTOR PETERSON.
